DRAFTING INSTRUMENT FOR DRAWING
SCALED ORTHOGRAPHIC VIEWS AND
AXONOMETRIC VIEWS

David D. Miller, 259 S. Robertson Blvd.,
Beverly Hills, Calif. 90213

Filed Jan. 13, 1970, Ser. No. 20,905

Term of patent 14 years

Int. Cl. D10—08

U.S. Cl. D52—6

FIG. 1 is a top plan view of a drafting instrument for drawing scaled orthographic views and axonometric views showing my new design, the bottom plan view being substantially plain; and

FIG. 2 is an edge view thereof on a reduced scale as seen from the right of FIG. 2.

I claim:

The ornamental design for a drafting instrument for drawing scaled orthographic views and axonometric views, substantially as shown and described.
